UNITED STATES PATENT OFFICE.

MELVILLE E. PETERS, GEORGE H. FATH, AND ALBERT F. MILLER, OF DENVER, COLORADO, ASSIGNORS TO THE PETERS PATENT RIGHTS COMPANY, OF DENVER, COLORADO, A CORPORATION OF COLORADO.

SIDE-TURN-IN WIPER FOR WRAPPING THE SIDE EDGES OF BOXES WITH GUMMED BLANKS.

1,244,540.

Specification of Letters Patent.

Patented Oct. 30, 1917.

Original application filed November 5, 1915, Serial No. 59,860. Divided and this application filed September 25, 1916. Serial No. 122,063.

To all whom it may concern:

Be it known that we, MELVILLE E. PETERS, GEORGE H. FATH, and ALBERT F. MILLER, citizens of the United States of America, residing at the city and county of Denver and State of Colorado, have invented new and useful Side-Turn-In Wipers for Wrapping the Side Edges of Boxes with Gummed Blanks, of which the following is a specification.

Our invention relates to a new and improved type of side turn-in wipers for wrapping or covering the open edges of boxes with gummed blanks, and the objects of our invention are:

First. To provide oppositely arranged co-operating side turn-in wiper mechanism that moves reciprocally in segmental paths and that act simultaneously together on opposite sides of boxes of various sizes and that will hold the edges in and neatly and quickly glue them to the interior surfaces of the boxes.

Second. To provide a simple high speed, reliable and artistic wrapping and covering mechanism for folding the edges of blanks over into and adhesively wrapping them against the inside surfaces of the open edges of boxes.

We attain these objects by the mechanism illustrated in the accompanying drawings, in which:

Figure 1 is a vertical transverse sectional view of a portion of a box wrapping machine, provided with the improved side turn-in wiper mechanism.

Fig. 2 is a vertical sectional view of one of the side turn-in wiper mechanisms and co-operating parts.

Fig. 3 is a front view of the same.

Fig. 4 is a plan view thereof.

Fig. 5 is an elevation of the rock lever which operates the slide block carrying the side turn-in blade.

Fig. 6 is a plan view of the slide block, the turn-in blade being removed.

Fig. 7 is a horizontal sectional view on the line 7—7 of Fig. 3.

Fig. 8 is a side view of the segment block which carries the slide block.

Fig. 9 is a front view thereof.

Fig. 10 is a vertical sectional view on the line 10—10 of Fig. 1; and

Figs. 11 and 12 are views respectively of a tight wrap and a loose wrap blank.

Similar letters refer to similar parts throughout the several views.

Referring to the drawings:

The mechanism illustrated in Figs. 1 and 2 illustrates our invention. In these views, as well as in all of the other views, the numeral 1 designates the turn-in wipers.

Our side turn-in wiper mechanism is arranged to receive boxes between them that vary in sizes from about $1\frac{1}{2}$ inches wide by 3 inches long to about 12 inches wide by about 20 inches long.

The boxes adapted to be wrapped are paste board boxes either with stayed or unstayed corners, and the blanks or labels are preferably made of thin, smoothly calendered white plain paper cut out into a form, as shown in Figs. 11 and 12, and they are coated with gum, either wholly or partially on one side, as shown in Figs. 11 and 12.

These blanks or labels are adhesively wrapped or covered around and against the outside surfaces of the boxes before they are submitted to our present side turn-in mechanism, and they are fed either by hand or by any suitable automatically operating mechanism between our side turn-in mechanism, each box having the edges of the blank projecting above the edges of the box far enough to be folded over into and glued against the interior surfaces of the opposite sides of the box.

After each box has had its open side edges wrapped, it is discharged from our present side wrapping mechanism.

Just before and instantly after our side turn-in mechanism, the boxes are subjected to end turn-in mechanism which acts co-operatively with our herein described side turn-in mechanism to properly wrap the open edges of each box.

This end turn-in mechanism does not, however, form a part of our present invention, and it is not either illustrated or de-

scribed herein; and we have not described the means for feeding the partially wrapped boxes to and for discharging the completely wrapped boxes from our present side turn-in wrapper mechanism, as they do not form a part of it. This end turn-in mechanism, however, is illustrated and described in our pending application Serial No. 122,064, filed September 25, 1916. Our present side turn-in wiper mechanism, however, forms a divisional part of our pending application for a patent for a box wrapping machine, Serial No. 59,860, filed November 5, 1915.

15 These side turn-in wrappers 1 comprise preferably strips of metal which are secured to a slide block 2, by a clamping strip 3, that is clamped to the head block by a clamping bolt 4, that is threaded into the slide block 2. This head block is provided with a rearward extending portion which terminates in a cross bar 5, the terminal ends of which are arranged to form trunnions having rollers 6 that bear in the yoke-shaped ends of two arms 7.

20 The detail construction and arrangement of this side turn-in mechanism is as follows:

To the top of the table on opposite sides of its longitudinal center and at equal distances from it we secure two head blocks 8, which support the side turn-in mechanisms. The side turn-in mechanisms of these two head blocks face each other, and as they are exactly alike a description of one will suffice 25 for both.

25 Each head block consists of a base portion 9, that is slidably mounted to be moved in a horizontal plane in a transverse slideway 10, formed in the table, and a vertically 30 movable chuck block 11, that is vertically adjustable upon upwardly projecting standards 12 that are formed on the base 9. The standards are yoke-shaped and are provided with guideways and each chuck block is 35 provided with a capped lug portion 13, that is slidably mounted in the guideway of the standard. A threaded rod 14 is rotatably mounted at its upper end in a bushing 15 at the top of the standard and threads down 40 through the lug 13 of the chuck block, its lower end resting in a bearing 16 in the adjacent end of the base 9. The threaded rod is adapted to receive a wrench to turn it to raise or lower the chuck block which has 45 a vertical movement on the standard sufficient to allow it to be adjusted to all heights or depths of boxes the machine will wrap. This chuck box extends down through a slot in the table, when adjusted for boxes 50 of slight depth, and it is adjustably movable up and down to accommodate boxes of different depths, and is fixed in adjusted positions by its cap 17, which can be clamped tightly to the standards. The chucks face the 55 opposite sides of the box that is to be wrapped

(see Fig. 1), and the opposing side members 18 of each chuck are each provided with a semicircular slideway 19, and in each pair of slideways is mounted a segmental block 20, which therefore travels in a semicircular path and is moved in this path by a combination of link and lever members which are constructed and act as follows:

75 The segment block is of the form shown in Figs. 8 and 9, and is provided with a depending bifurcated lug 21, to which one end of a link 22 is pivoted. The lower end of this link is provided with an oblong slot and is pivotally connected through this slot by a pin 23 to the upper end of a vertically 80 reciprocable bar 24, which is slidably mounted in a guide 25 that is formed on a depending portion of the head block.

85 The lower portion of each of the bars 24 is provided with an adjustable collar 26, that rests on a spring 27 that is housed in a socket 28 that is attached to a cross bar 29, which cross bar is given a vertical reciprocating movement by a forked lever 30, to which it is bolted, and which is operated by a cam 31, which is secured upon the main driving shaft 32. The upper end of the forked lever 30 moves in a guideway of a standard 33, which is bolted to the bed plate. The upper portions of the bars 24 are square, 95 but the lower portions thereof are rounded and extend through the springs 27, and sockets 28, to allow for vertical adjustments to correspond with adjustments of the head blocks to fit boxes of different heights.

100 Each bar 24 has a rib portion 34, that has a cam curve 35 at its upper end that engages a roller 36, that is mounted on the depending member 37 of a rock arm. This rock arm comprises a long hub 7^A that is pivotally mounted on a pin 38, that extends through it and the sides of the chuck, the depending member 37, and the two arms 7, spaced a short distance apart and extending upward, the end of each of which terminates in a 110 fork 39, in which lie the rollers 6 which are mounted on opposite sides of the end portion 5 of the sliding block 2, which is reciprocally mounted in a slideway 40 formed in the top of the segment block 20. Arms 115 41 project from the opposite ends of the hub 7^A, the outer ends of which are connected to the lower ends of springs 42, that act to normally hold the rollers in contact with the ribs 34 of the bars 24. The opposite ends of the springs are connected to pins 43, that are secured to the sides of the chuck. The sliding block 2 is provided with the cap 3, that is arranged to clamp the side turn-in blade 1, as shown by Figs. 2 and 4. 125 The side turn-in blades are of a length corresponding to the inside length of the boxes being covered.

130 Along the front face of each chuck we secure a bar 44, against which the upper edges

of the sides of the boxes bear, when the turn-in blades bend the extended portions of the sides of the blank over against the inner faces of the sides of the box, as shown by the dotted lines in Fig. 2.

These two chuck heads and their bases are arranged to be moved in unison together toward or away from the longitudinal center of the machine in the following manner:

- 10 Each head block is formed with an opening in which is secured an internally threaded bushing 45, in which is screwed a plug 46, having a square hole, the outer end of the plug having an annular groove 47.
- 15 Through these plugs passes a square rod 48, the ends of which are rounded and enter bushings in the sides of the table. A threaded rod 49 extends parallel with and adjacent to the square rod 48, and upon the 20 end portions of the threaded rod are screwed followers 50, comprising hub members having arms 51, the outer ends of which are bifurcated, and straddle the annularly grooved ends of the plugs 46. Thus by turning the crank handle 52, on the end of the threaded rod 49, the said rod is rotated, and the head blocks are moved inward or outward in their slideways 10.

The object of threading the plugs 46 to 30 the bushings 45 is as follows: When the boxes pass from the first into the second stage position, the head blocks stand in such positions relatively to each other that the boxes may pass readily between the bars 35 44, without touching them, but after they have reached their proper position it is necessary that their sides should be engaged by the said bars 44, and to accomplish this a slight inward movement is given to each 40 head block by turning the square rod by which the plugs are turned, and as the plugs when turned by the square rod are held against lateral movement by the followers 50, the head blocks are thereby moved in or 45 out according to the direction of rotation of the plugs. The square rod is turned in the following manner: A cam disk 53 is mounted on the main driving shaft 32, and has a cam 54, which engages a roller 55 on one 50 member of a double crank arm, which is supported in a bracket 56, that is bolted to the bed plate of the machine. The other arm 57 connects with the lower end of a connecting rod 58, the upper end of which is pivotally 55 attached to a lever 59, which is mounted on the adjacent end of the square shaft. It will thus be seen that the cam 54, imparts movement to the connecting rod 58, by which the lever 59 is rocked and the shaft turned.

60 The chucks having been adjusted with their guide strips in operative relation to receive a box and blank between them, the segment block and the sliding block operate to cause the side turn-in blade 1 to turn in 65 the upwardly projecting side edges of the

blank into the interior and against the inside surfaces of the box in the following manner:

When the bars 24 are raised by the cam 31, the cam curves 35 at the upper end of the bars first engage the rollers 36 of the rock 70 arm, which causes the lower ends of the rock arms to swing out and their upper end to push the sliding blocks 2 forward toward the box, which causes the side turn-in blades to move horizontally forward and engage 75 the projecting edges of the blank, and in moving forward they barely clear the top side edges of the box; then as they reach the end of their inward stroke the pins 23 at the top of the bars 24 have by this time moved 80 up with the bars to the upper end of the slots in the links 22, which connect the bars with the segment blocks 20, and thus lift the segment blocks, causing them to move in an arc of a quarter of a circle in the semi-circular 85 curved slideways of the chucks, which causes the sliding blocks and the turn-in blades to tilt upward into vertical positions, and as the blades tilt over the side edges of the box they bend the edges of the blank over into 90 the box and against its inside surfaces and the blades press the blank tightly against the inside surfaces of the box when it swings into a full and a trifle more than a full vertical position, which brings a decided side 95 pressure of the blades 1, against the inside of the box, thus firmly pressing the edge of the blank against the inside surface of the box, the turning-in blades thus rolling over the edge of the box and pressing flat against 100 its inside surface, the sides of the box with the turned-in blank being pressed between the said blades and the bars 44.

When the segment blocks move upward in their curved slideways 19, in the chucks, 105 they lift the rollers 6, of the sliding block 2, out of the yoke ends 39, of the arm 7, and swing them up into such a vertical position as is necessary to cause the finger blade to press and thus glue the edges of the blank 110 against the inside surface of the opposite sides of the box.

Our present invention provides a positively operative side turn-in mechanism and one that is easily and quickly adjusted to boxes of the different sizes that it is made to receive, and while we have illustrated and described the preferred construction and arrangement of our invention, we do not wish to be limited to the construction and arrangement shown, as many changes might be made without departing from the spirit of our invention.

Having described our invention, what we claim as new and desire to secure by Letters 125 Patent is:

1. In a side turn-in wiper mechanism, the combination of the table frame with the side turn-in wipers comprising the vertically adjustable chuck blocks and their horizontally 130

adjustable bases, said chuck blocks facing each other on opposite sides of the longitudinal box and blank feeding movement, said chucks being provided with a semi-circularly curved slideway, a segment block reciprocally mounted in said slideway, a plate reciprocally mounted in said segment block and provided with a side turn-in wiper block, and means for operating said side turn-in wiper mechanism.

2. In a side turn-in wiper mechanism, the combination of the table frame with the side turn-in wipers comprising the vertically adjustable chuck blocks and their horizontally adjustable bases, said chuck blocks facing each other on opposite sides of the longitudinal box and blank feeding movement, said chucks being provided with a semi-circularly curved slideway, a segment block reciprocally mounted in said slideway, a plate reciprocally mounted in said segment block and provided with a side turn-in wiper block, and means including cam actuated links and rods connected to said segment block and said plate, whereby said side wipers engage and wrap the top side edges of the blank.

3. In a side turn-in mechanism for the open edges of boxes, the combination of the table frame provided with transverse slideways, with the side turn-in bases slidably mounted in said slideways, the chucks vertically adjustable in said bases, the semi-circular slideway in said chucks, the segment block fitting slidably in said slideway and provided with wiper blade members adapted to engage the opposite sides of said boxes, the link connected to said segment block at one end and provided with an oblong slot at its opposite end, the vertically reciprocating bar pivotally connected to the slotted end of said link, and cam actuated means for imparting an intermittent vertically semi-circular curved reciprocal movement to said segment.

4. In a side turn-in mechanism, the combination of the table frame provided with adjustable transverse and vertical movement chucks provided with a semi-circular curved slideway, a segment block reciprocally mounted to move in the curved path of said slideway, means including a cam actuated reciprocating bar for reciprocating said segment block in said curved slideway, a plate reciprocally mounted in said slideway, a blank engaging and turning-in blade clampingly secured to the outer end of said plate and arranged to engage and move said blank in a horizontal plane first over the edge of the box, a rock arm pivotally connected in said chuck and provided with two forked ends spaced apart, trunnion ends on the inner end of said plate arranged to bear pivotally and loosely in said forked ends, the opposite end of said rock arm be-

ing provided with a roller, and a cam on said vertically reciprocating bar arranged to engage said roller and tilt said rock arm to cause said wiper blade to tilt over the edge of the box and press the blank against and into engagement and wrapping relation to the interior surface of said box.

5. In a side turn-in mechanism, the combination of the table frame, provided with a transverse slideway, the opposing chucks adjustably mounted in said slideway and arranged to receive a partially wrapped box between them, provided with the curved slideway, the segment block reciprocally mounted in said slideway, and the sliding wiper blade supporting plate reciprocally mounted in said segment block, with a vertical bar reciprocally mounted in said table frame below each chuck, the lower ends of both of which are connected together by a cross bar, means for laterally adjusting said chucks and rods toward or away from the center of said table frame, means including links for connecting the upper end of each bar with said segment block, and means including a cam fork secured to said cross bar and a cam for reciprocating both of said rods and the segment block of each chuck in its curved slideway in unison.

6. In a side turn-in mechanism, the combination of the table frame provided with a transverse slideway, the opposing chucks adjustably mounted in said slideway and arranged to receive a partially wrapped box between them, provided with the curved slideway, the segment block reciprocally mounted in said slideway, and the sliding wiper blade supporting plate reciprocally mounted in said segment block, with a vertical bar reciprocally mounted in said table frame below each chuck, the lower ends of both of which are connected together by a cross bar, means for laterally adjusting said chucks and rods toward or away from the center of said table frame, means including links for connecting the upper end of each bar with said segment block, means including a cam fork secured to said cross bar and a cam for reciprocating both of said rods and the segment block of each chuck in its curved slideway in unison, and means including a cam surface on each of said rods, and a rock arm in engagement at one end with said rod's cam surface, and having a releasing pivotal connection with said reciprocating plate of each chuck for reciprocating said plate and its side turn-in wiper on the blank and box wrapping stroke of its reciprocal movement, and resilient means connected to each chuck and rock arm for moving said rock arms and said plates on the inoperative stroke of their reciprocal movement.

7. In a side turn-in mechanism for the open edges of boxes, the combination of the

table frame provided with a transverse slideway and with a power driven shaft, the operative chucks adjustably and slidably mounted in said slideway, and their wiper 5 operating mechanism, and the vertically reciprocating wiper actuating rods and the cross bar at the lower ends of said rods, with a boxing connected to said cross bar provided with a vertical slideway in which 10 said rods are adjustably mounted, an adjustable resilient joint in said boxing arranged to cushion the upward resilient stroke of said bar's reciprocal movement, a cam mounted on said power driven shaft, a cam 15 fork provided with a roller in engagement with said cam, a slideway in said cross head in which said cam fork is reciprocally supported, and means for securing said cam fork to the cross bar of said chuck's reciprocating rods.

8. The combination with a table having oppositely arranged head blocks slidably mounted therein, adapted to grip or release boxes of different predetermined sizes, of 20 aligned plugs in threaded engagement with said heads, having square axial apertures and annularly grooved at their outer ends, a square rod mounted at its ends in said table and passing loosely through said plugs, a manually operated right and left hand threaded rod extending parallel with the 25 square rod and mounted at its ends in said table, followers in threaded engagement with said threaded rod and having bifurcated ends which engage the grooved ends of said 30 plugs, cam actuated means for imparting a 35

partial rotation to said square rod to move the head blocks reciprocally a short distance simultaneously in rapid successive order toward or away from each other, and means 40 independent of the short reciprocal box gripping and releasing means, for moving said blocks simultaneously toward or away from each other to positions on which they will receive boxes of different sizes. 45

9. The combination with a support and opposite head blocks slidably mounted therein, of plugs in threaded engagement with said blocks, having square axial apertures and annularly grooved outer ends, a square 50 rod rotatably mounted at its ends in said support and passing through said plugs, an arm on said square rod, a double-armed rock lever, a rod connected to the arm on said shaft and one arm of said rock lever, a 55 roller on the other member of said rock lever, and a cam for engaging said roller thereby to rock said double armed lever, a manually operated right and left hand threaded rod extending parallel with the 60 square rod and mounted at its ends in said support, and followers threaded to said threaded rod and having bifurcated ends which engage the grooved ends of said plugs.

In testimony whereof we affix our signatures in presence of two witnesses.
